US00D490711S

(12) **United States Design Patent** (10) Patent No.: **US D490,711 S**
 DeLuca et al. (45) Date of Patent: ** Jun. 1, 2004

(54) **INFLATABLE PACKING MATERIAL**

(75) Inventors: **Nicholas P. DeLuca**, Mill Valley, CA (US); **Oliver M. Reyes**, Berkeley, CA (US); **Philippe M. Jacques**, Davis, CA (US)

(73) Assignee: **Free-Flow Packaging International, Inc.**, Redwood City, CA (US)

(**) Term: **14 Years**

(21) Appl. No.: **29/167,670**

(22) Filed: **Sep. 17, 2002**

(Under 37 CFR 1.47)

CLAIM

The ornamental design for an inflatable packing material, as shown and described.

DESCRIPTION

FIG. 1 is an isometric view of an inflatable packing material showing our new design;

FIG. 2 is a top plan view thereof, the bottom being a mirror image of the top;

FIG. 3 is an isometric view of FIG. 1, showing the inflatable packing material in an inflated condition;

FIG. 4 is a top plan view thereof, the bottom being a mirror image of the top;

FIG. 5 is a front elevational view thereof, the rear being a mirror image of the front; and,

FIG. 6 is a right side elevational view thereof, the left side being a mirror image of the right side.

1 Claim, 4 Drawing Sheets
